UNITED STATES PATENT OFFICE.

WLADYSLAW NOGA, OF DETROIT, MICHIGAN.

SILK AND YARN THREAD TENSIONING AND WAXING DEVICE.

Application filed June 23, 1924, Serial No. 721,921. Renewed May 27, 1926.

My invention relates to improvements in devices for applying wax and tension to any and all kinds of threads used by all knitting machines or other thread handling machines, 5 the principal object being to provide an extremely simple and easily attached device of this character which will be highly efficient for effectively waxing and tensioning a thread as it travels to the machine, the 10 construction of the device being such as to readily permit any required adjustments.

With the foregoing in view, the invention resides in the novel subject matter herein-after described and claimed, the description 15 being supplemented by the accompanying drawing.

Figure 1 is a perspective view of a portion of a knitting machine equipped with my invention.

20 Figure 2 is an enlarged perspective view partly in vertical section.

Figure 3 is a partial top plan view.

In the drawing above briefly described, the numeral 1 designates an arm which carries tensioning and waxing means for silk, 25 yarn, or any other kind of thread. This arm is connected at one end by a horizontal pivot 2, with an arm carrier 3, which carrier comprises a base 4 having a central opening 5, and a pair of upstanding ears 6 rising from the base at opposite sides of said opening. The arm 1 is pivoted between the upper 30 ends of the ears 6.

The carrier 3 rests on a supporting head 35 7 and is pivoted thereto by a vertical pivot 8. The head 7 preferably includes a horizontal plate-like portion 9 upon which the base 4 of the carrier 3 rests, said head being also provided with a horizontally disposed bearing 10 which is contractible, for instance, by 40 means of a screw 11. A horizontal supporting arm, preferably in the form of a rod 12, has one end secured in the bearing 10, and the other end of this arm is preferably provided with a clamp 13 by means of which it 45 may be secured to an arm 14 of a knitting machine. In the preferred form of construction, the clamp 13 comprises an arched body whose legs 15 are adapted to straddle a portion of the arm 14, one of said legs being provided with one or more set screws 16 to secure the clamp in place. Rising 50 from and formed integrally with the crown portion of the clamp body, is a post 17 having a horizontal opening 18 forming a bear-

ing for the end of the rod 13, remote from the head 7. This rod may be readily adjusted in the opening 18, but a set-screw 19 is threaded through the post 17 to hold said rod in adjusted position.

In the preferred form of construction, a bearing post 20 rises from the free end of the arm 1 and is provided adjacent the upper side of said arm with a cup 21 which may if desired contain a lubricating oil. A sleeve 22 rotatably surrounds the post 20 and is provided at its upper end with a bearing cap 23, between which and the post, a bearing ball 24 is interposed. A bearing bushing 25 is provided in the lower end of the sleeve 22, and this end carries a disk 26 which closes the cup 21 and is formed with a downturned edge 27 around said cup. The disk 26 and its edge 27 coat with the cup 21 to protect the post 20 and the interior 70 bearings of the sleeve 22 against dust and other foreign matter. The thread to be waxed, indicated in the drawing at 28, passes through a guide eye 29 on the arm 1 and passes across the upper side of the disk 26. 75 A block of wax or the like 30, (large or small) of annular form, loosely surrounds the sleeve 22 and rests on the thread, so that as the latter moves between the disk and the block of wax or the like, it will be treated in 80 the desired manner, with the numerous well known results. Furthermore, the tension on the thread will prevent drop stitches.

The construction shown and described is 85 simple and inexpensive, may be easily attached, and is readily adjustable as occasion 90 may require. Furthermore, it is highly efficient and desirable and for these reasons, the construction shown is preferably followed. However, within the scope of the invention 95 as claimed, numerous changes may be made.

I claim:

1. A device of the class described, comprising a carrying arm, an arm carrier comprising a horizontal base having a central opening and a pair of spaced ears rising from said base at opposite sides of said opening, said arm being pivoted between said ears for vertical movement, a head having a horizontal portion on which said base rests, a vertical pivot passing through the afore-said opening and connecting said carrier with said head, the head being also formed with a horizontal contractible bearing, a horizontal arm having one end secured in 105 110

said bearing, and an attaching clamp having a bearing in which the other end of said horizontal arm is secured.

2. In a yarn waxing attachment for a knitting machine, a clamp adapted to be secured upon a frame member of the machine, said clamp having a horizontally disposed bearing opening, a horizontal rod having one end received in said opening, means associated with the clamp for holding said rod

in place, a head at the other end of said rod having an opening through which the latter passes, means for securing said head upon said rod, an arm carrier pivoted on a vertical axis to said head, and a carrying arm for waxing means pivoted on a horizontal axis to said carrier. ¹⁵

In testimony whereof I have hereunto affixed my signature.

WLADYSLAW NOGA.
